FURNACE VALVE CONSTRUCTION

Jay L. Roof, Hamburg, N. Y.

Application August 1, 1951, Serial No. 239,710

3 Claims. (Cl. 263—15)

1

This invention relates to the reversing valves of regenerative furnaces, such as open hearth furnaces used in the production and refinement of steel, soaking pits for the heating of steel ingots, and other fuel-fired furnaces whose combustion air is preheated.

In exemplary way the invention will be described as it may be employed in open hearth furnaces.

An open hearth furnace consists of a furnace chamber having a hearth, front and back walls, end walls, and roof constructed of refractory brickwork, supported and externally reinforced and tied by means of a steel framework. The hearth of the furnace is dished, providing a basin which sustains the charge of metal and ingredients required to produce a specified "heat" of steel. At the two ends of the furnace ports are provided and each port communicates with a regenerator (or recuperators) containing a body of checkerwork formed of refractory brick. Flues lead from each regenerator and such regenerator flues are connected to a single flue leading to a stack, which delivers the products of combustion of the furnace into the outer atmosphere. At the point where the regenerator flues merge with the stack flue a set of reversing valves or dampers is provided. During furnace operation fuel and air are admitted through the port at one end of the furnace, and a column of flames and hot gases is projected across the hearth to supply the required heat to the furnace charge. The hot gases or products of combustion exit through the port at the opposite end of the furnace, and stream through the regenerator associated with the latter port, whence they flow through the regenerator flue to the stack flue and thence to the stack. In this way the body of checkerwork in the regenerator receives large stores of heat from the waste gases or products of combustion of the furnace.

From time to time the furnace is reversed; that is to say, the port which had been serving as the firing port becomes the outgo port, with the effect that the body of checkerwork of the regenerator of such port is then heated by the products of combustion. The port which had been serving as the outgo port becomes the firing port, and the air for combustion of the fuel delivered through such port, admitted to the flue system at the reversing valves, streams through the hot checkerwork and is preheated to augment combustion and the development of high temperatures within the furnace chamber. In effecting a furnace reversal, the reversing valves are oper-

ated alternately to connect the flue of each regenerator to the stack flue and to the inlet for combustion air. Accordingly, while the regenerator at one end of the furnace serves to preheat the combustion air, the regenerator at the opposite end of the furnace is being charged with heat by the products of combustion. By effecting a periodic reversal of the valves a substantially continuous supply of preheated air is furnished, and so the operation of the furnace is continued. During such operation slag is flushed off the molten metallic charge and the required metallurgical materials are added, until at length the metallic charge is reduced to desired analysis. Then the heat is tapped.

The reversing valves incorporated in the flue system of an open hearth furnace are constructed of metal, and due to the high heat to which such valves are exposed in service the cooling of the valves is essential. The prevailing practice is to cool the valves by means of circulating cooling water. The application of cooling water to the reversing valves is expensive, from the standpoints of equipment cost, maintenance, power required to pump the water, and the cost of obtaining a supply of suitable water and an acceptable place for water disposal. Furthermore, the chemical analysis of the water is a factor presenting difficulties in many installations, since the water must be of such characteristics that it will not produce sediment or otherwise cause accumulations of solid particles within the hollow bodies of the valves, which will result in a constriction of the water passages and a premature failure of the valves under the influence of the heat to which they are exposed.

I have succeeded in eliminating the need for water-cooling valves and dampers, as disclosed in Letters Patent 2,148,713 and 2,285,533, granted on my applications on February 28, 1939, and June 9, 1942, respectively. Referring to these patents, I employ a particularly effective circulation of air to guard ordinary dampers and valves against the destructive influence of the hot waste gases or products of combustion of industrial furnaces. In the case of reversing valves of the sort indicated in the foregoing context, the problem is particularly difficult, and my present invention is found in certain new and useful improvements, whereby the use of cooling water may be eliminated in valve installations of the sort indicated herein.

The invention will be understood upon reference to the accompanying drawings, in which:

Fig. 1 is a fragmentary view in horizontal sec-

tion of the flue system and stack of an open hearth furnace, showing a set of reversing valves and a stack damper embodying my invention, the plane of section being indicated at I—I in Fig. 2 of the drawings;

Fig. 2 is a vertical, sectional view of the flue system and valves, as seen on the planes II—II of Fig. 1;

Fig. 3 is a vertical, sectional view of the installation, as seen on the plane III—III of Fig. 1;

Fig. 4 is an isometric view of one of the seats of the reversing valves; and

Fig. 5 is a fragmentary view showing one of the reversing valves as shown in Fig. 1, but to larger scale.

Referring to the drawings the two regenerators of an open hearth furnace are fragmentarily shown at 2 and 3, connected by regenerator flues 4 and 5, respectively, to a flue 6 that opens into the bottom of a stack 7. Such flue system is conventionally constructed of concrete 8, lined with refractory brickwork 9.

The valve system of the furnace comprises a reversing valve 10 controlling communication between regenerator flue 4 and stack flue 6, a reversing valve 11 controlling communication between regenerator flue 5 and the stack flue, and a stack valve 12 controlling communication between the stack 7 and both regenerator flues 4 and 5. Above the flues at the point where the stack flue 6 merges with the regenerator flues 4 and 5, an air-box 13 is provided, and from such air-box a duct 14 leads to a powerfully driven fan or blower (not shown) that delivers air into the box. In one side wall of the air-box a removable door 14a is provided, and this door may be opened in the event of fan failure, to admit air to the box from the outer atmosphere.

The reversing valves 10 and 11, and the stack valve or damper 12 are mounted for vertical travel on valve seats 15, 16 and 17, respectively. In Fig. 4, the structure of the valve seats 15 and 16 will be readily understood. Each of such seats comprises a hollow metal frame, having a central body portion 18, and two marginal flanges 19, 19. In service such valve seats are mounted in inclined position, as shown in Fig. 2, and the central body portion 18 provides the seat proper, upon which a valve (10 or 11) is adapted to slide upwardly and downwardly, laterally guided and held in place by and between the two marginal flanges 19, 19. The central body portion 18 includes two windows 20 and 21, resulting in the body portion 18 actually comprising two vertical edge portions 22 and 23 that are laterally connected by horizontal portions 24, 25 and 26. The portions 22 to 26 form the seat upon which the valve is adapted to seat and vertically to slide.

The valve seats 15 and 16, each constructed as shown in Fig. 4, are incorporated and sealed in the flue and air-box structure, in the mutually inclined positions shown in Fig. 2. The lower windows 20 of the seats are arranged to define the lines of flow between the regenerator flues 4 and 5, respectively, and the stack flue 6, while the upper windows 21 of the two seats are arranged respectively to define the lines of flow from within the air-box 13 to the flues 4 and 5. Each of the valve-and-seat assemblies 10, 15 and 11, 16 are enclosed and hermetically sealed to the air-box and the respective flues 4 and 5 by means of hoods 27 of steel plate, and from the top of each valve 10 and 11 a rod 28 extends upwardly through the associate hood, and is connected to a suitable valve-adjusting mechanism, not shown

but known to the art. Upon reference to Fig. 2 it will be understood that each of the valves 10 and 11 may be vertically adjusted on its inclined seat, between a position in which one of the windows 20 and 21 in the seat is open and the other closed.

In Fig. 2 the valve 10 is shown in its lower position, closing the lower window 20 in its seat, and thus blanking communication between regenerator flue 4 and stack flue 6, and leaving the upper window open so that air may flow from the air-box 13 to the said flue 4, whence such air streams through the regenerator 2 (Fig. 1) and is preheated for sustaining combustion of fuel delivered to the corresponding port of the furnace, which is then serving as the firing port. At this time the valve 11 is sustained in elevated position on its seat, closing the upper window 21 and blanking the passage between the air-box 13 and regenerator flue 5, while leaving the lower window 20 open, and letting flue 5 stand in open communication with the stack flue 6 (Fig. 1), whereby under the suction or draft of the stack the hot products of combustion are drawn through regenerator 3 from the associate furnace port, which is then serving as the outgo port. Thus, the valves 10 and 11 remain positioned until the regenerator 2 has yielded most of its effective heat to the combustion air and the regenerator 3 has received a store of heat from the products of combustion. Then, the furnace is reversed; that is, the flow of fuel is cut-off from the firing port of the furnace and delivered to the port which had been serving as the outgo port; and substantially simultaneously with this fuel reversal the positions of the valves 10 and 11 are reversed—the valve 10 is raised to open window 20 and close window 21 in its seat 15, and valve 11 is lowered to open window 21 and close window 20 in its seat 16. Manifestly, such reversal of the positions of the valves 10 and 11 permits combustion air to flow from the air-box 13 through flue 5 and regenerator 3 to the port of the furnace which has become the firing port, while the hot products of combustion are drawn from the opposite port of the furnace through the regenerator 2 and flues 4 and 6 to the stack. In such way a furnace equipped with reversing valves is operated, and the reversal of the furnace is repeated as need be during furnace operation.

The stack valve or damper 12 is adjustable on its seat 17 to regulate the area of the stack flue 6 and the degree of the stack draft effective upon the furnace. The particular construction of the stack damper and its seat will be considered later herein.

The reversing valves and their seats are hollow, constructed of metal, preferably steel or iron, and provision is made for a flow of cooling air through the hollow bodies of the valves and seats, to dissipate heat and safeguard them against the high temperatures to which they are exposed in service. The construction and arrangement of the valves and seats with the flue system and air-box are such that an effective flow of cooling air is maintained throughout the hollow bodies of the valves and seats, no matter what the position of adjustment of the valves may be.

Considering first the valves 10 and 11, it will be understood that adjacent the top edge of each valve one or more inlets 29 are provided in the back-wall of each valve, the back-wall being the wall that bears and slides upon the associate valve seat. Adjacent the bottom edge of each valve one or more outlets 30 are formed in the

front wall of the valve. It will be perceived that the upper ports or windows 21 in the valve seats 15 and 16 are so extended vertically that, no matter whether the valves 10 and 11 are raised or lowered (cf. the positions of the two valves in Fig. 2), the inlets 29 stand in open communication with the air-box 13, whereby air is continuously fed into the hollow valve bodies under the super-atmospheric pressure of the conventional combustion air fan (not shown) which feeds the air-box. When a valve is in raised position (cf. valve 11, Fig. 2) the outlet 30 of the valve is exposed to the stack draft then effective in flues 5 and 6. On the other hand, when the valve is in its lowered position, closing the lower window 20 in its seat (cf. valve 10, Fig. 2) the outlet 30 is exposed to the suction effect of the stream of air drawn from the air-box 13 and through flue 4 and regenerator 2 into the furnace. Thus, it will be understood that cooling air continuously flows through the hollow bodies of the valves under the effect of stack draft or suction, augmented by the positive pressure at which the air is delivered to the air-box.

Referring to Figs. 4 and 5, it will be understood that air inlets 31 are provided in the top and center cross members 25 and 26, respectively, of each valve seat, and outlets 32 are provided in the lower cross member 24. Regardless of the position of either valve on its seat air under pressure in the air-box 13 enters the hollow body of the seat, and flows in the directions of the arrows in Fig. 4 to the outlets 32, which are constantly exposed to the suction effect of the stack draft prevailing in flue 6. As the arrows indicate, a uniformly distributed flow of air is maintained throughout all portions of the hollow body of the valve seat, thereby dissipating the heat to which the structure is subjected during furnace operation. The valve seats, as thus cooled by an injected and drafted circulation of cooling air, in combination with the air cooled valves, provides a reversing valve installation that avoids the expensive use of cooling water.

It is to be noted that air cooled valve seats in accordance with my invention may be employed with air cooled valves of the type disclosed in my Patent No. 2,285,533. Furthermore, the air-cooled valve and seat structure of the invention may be used in the flue systems of furnaces using other forms of heat-exchangers than regenerators, and in flues other than stack flues.

The stack valve or damper 12 and its seat 17 may both be air cooled in accordance with my invention. The air outlet 34 (Fig. 3) of the damper 12 is constantly exposed to the draft or suction prevailing in the stack flue 6, and under such suction air is drawn through an inlet 33 from the outer atmosphere, and, sweeping through the hollow body of the damper, safeguards the damper from injury due to heat. The damper seat 17 is generally similar in structure to the seats 15 and 16, save that the seat 17 need have only two hollow cross members 24a and 25a. From the cross member 25a the seat is continued upwardly in two hollow side portions 19a of L-shape in cross section. These hollow side portions are open at their upper ends, forming air inlets, while air outlets 35 are formed in the cross members 24a and 25a that stand in open communication with the stack flue 6, with the consequence that cooling air is sucked from the outer atmosphere downwardly through the hollow body of the damper seat into the flue 6. A continuous flow of cool air through the damper 75

and its seat is maintained, and the objects of the invention are realized.

In the appended claims the term "stack flue" will be understood to include a flue leading to an exhaust fan or other outlet than a stack, and the terms "duct" or "flue duct" indicate the two passages extending between the stack flue and the heat exchanger or regenerator. Additionally, it will be noted that within the terms of the claims various changes and modifications will occur to those skilled in the art without departing from the spirit of the invention.

I claim:

1. In a reversing valve system having two flue ducts communicating with a stack flue and having an air box for supplying air under pressure to a selected one of said flue ducts, the invention herein defined comprising a pair of hollow valve seats each having two spaced parallel side guides and three hollow cross members connecting the side guides, one of the cross members being located near each end of the guides and the third one being intermediate the ends of the guides, the hollow interiors of the guides and cross members all being in continuous communication whereby each seat is provided with a window-like air port between the intermediate cross member and one of the end cross members and a window-like hot gas port between the intermediate and other end cross member, said seats being positioned across the ends of the air box with the air ports thereof registering with the air box and with the gas ports thereof being positioned between one of said flue ducts and the stack flue, the intermediate and end cross frame member defining the air port having openings in the confronting surfaces thereof of which are always open to the air in said air box, the third cross member having an opening therein leading from the interior thereof to the gas port of which it constitutes one boundary, and a plate-like valve slideable on each valve seat between said guides on the face of the seat which is turned away from the air box and selectively movable from a position over one window-like port to a position over the other.

2. A reversing valve structure as defined in claim 1 wherein each plate-like valve is a hollow body having opposed face plates, one of which rests against the seat, the valve body being of a length such that when it completely closes the gas port it projects part-way across the air port, said face plate which is against the valve seat having an opening therein which is only in said part of the valve that always projects across the air port and which is of sufficient length to be exposed to the air port when the valve is in position to close either port, the hollow valve body having an opening therethrough adjacent its opposite end in the opposite face thereof.

3. A reversing valve system comprising two separate ducts opening into a stack flue and an air box adjacent the stack flue for selectively delivering air to either duct, a continuously hollow metal valve seat extending across each of said first ducts and across opposite ends of the air box and having a pair of window-like ports therethrough, one of which registers with its respective duct and one of which registers with an end of the air box, a hollow valve plate slideable on each valve seat on that face of the seat which is faced away from the air box, each valve being selectively movable from a position to cover either of said window-like ports and open the other, said hollow valve seat and valve each hav-

ing air inlet openings therein that are always opposed to the air in said air box, and having air outlet openings therein adjacent those points thereof which are most remote from the air inlet openings and which air outlet openings are always open to the gas stream flowing in the several ducts and the flue whereby a continuously forced circulation of cooling air is at all times provided through the valve seats and valves from the air box through the hollow valves and seats. 10
